UNITED STATES PATENT OFFICE.

WALTER WRIGHT, OF NEW YORK, N. Y., ASSIGNOR TO UNDERWOOD COMPUTING MACHINE COMPANY, OF NEW YORK, N. Y., A CORPORATION OF NEW YORK.

COMBINED TYPE-WRITING AND COMPUTING MACHINE.

1,271,820.

Specification of Letters Patent.

Patented July 9, 1918.

Application filed April 23, 1910. Serial No. 557,273.

To all whom it may concern:

Be it known that I, WALTER WRIGHT, a citizen of the United States, residing in New York, in the county of New York and State 5 of New York, have invented certain new and useful Improvements in Combined Type-Writing and Computing Machines, of which the following is a specification.

This invention relates to computing mechanism, particularly that which is combined with typewriting mechanism, and has to do principally with means for preventing premature or false movements of the keys.

One of the main objects of the invention 15 is to provide improved means for preventing the operation of any numeral key, any alphabet key, or any other carriage-controlling key of the typewriter, during the rotation of the computing mechanism; a part of 20 which is usually connected to the typewriter carriage for a denominational movement concomitantly with the letter-feeding movement of the carriage, whence, it becomes desirable that nothing shall occur to move the 25 carriage while the adding mechanism is rotating.

This feature of the improvement has for its object to provide a quickly acting key-locking mechanism, such that there will be 30 no interference with the operation of the keys, even when the latter are operated at very high speed, unless a false or premature stroke is made by the operator.

To this end, I provide a universal bar 35 which is directly actuatable by all of the alphabet keys, and moves idly at every key stroke. This universal bar is controlled by a locking mechanism which normally is held released by the primary escapement-wheel 40 of the computing mechanism. Said bar is constantly in position to be actuated by the key levers, and is actuated at every stroke thereof. It cannot check the key strokes, and hence the keys may be operated rapidly, 45 unless a key stroke be attempted while said primary escapement wheel is rotating and hence no longer holds the said universal bar unlocked. The numeral keys are preferably also controlled by the same key-locking 50 mechanism, by means of another universal bar or device.

The invention is shown in connection with the devices disclosed in my pending appli-

cation No. 554,452, filed April 9, 1910, in which a dog which releases the primary escapement wheel of the computing mechanism is connected directly to the paper carriage of the typewriter to be operated thereby; a rack being connected to said carriage, and a pallet, which is connected to said dog, being adapted to coöperate with said carriage rack to enable the carriage to actuate the dog in such a manner that the primary escapement wheel of the adding mechanism is released by said dog at the concluding portion of the letter-feeding movement of the carriage; said pallet being normally disengaged from said rack during the operation of the alphabet keys, and the numeral keys having means for moving said pallet into engagement with said rack to be operated thereby.

While the present improvements are of special value when combined with a paper carriage which controls or feeds the escapement wheel of the computing mechanism, they are also of value in some cases in which such an escapement wheel is released, fed, or controlled solely by the numeral keys without the intervention of the carriage.

According to another feature of the present improvements, the universal bar already referred to, which is operated at every stroke of every alphabet key, is also employed for the purpose of preventing concomitant operation of an alphabet key with a numeral key; there being provided for this purpose, as set forth in my application No. 556,378 filed April 19, 1910, now Patent No. 1,237,438, a set of mutually interfering blades, each of 90 which is movable to a common central position, so as to prevent operation of the others. One of these blades is connected to said universal bar, and the remaining blades are connected individually to the remaining 95 keys. Hence when a numeral key is depressed, it is impossible to depress an alphabet key, and vice versa.

Thus a simple structure prevents simultaneous operation of a numeral key and an 100 alphabet key, and also prevents operation of any key during the rotation of the computing mechanism.

The foregoing improvements are illustrated in connection with a checking device 105 which prevents premature reversal of the

movement of a numeral key. By a very simple construction, which permits very rapid operation of the keys, all the foregoing advantages are secured.

5 Also according to the present improvements, the spacing key of the typewriter, and also the tabulating keys which are usually provided for the carriage, are connected to the locking mechanism already referred to, so as to be controlled thereby as already set forth. A single device preferably extends from said universal bar to said space key and said tabulating keys, through which all the locking functions referred to can be performed; so that all of the keys which control the carriage are, by means of a very simple, easily operated and rapidly moving structure, prevented from operating said carriage during the rotation 20 of the computing mechanism, and are also prevented from operating concomitantly with any numeral key.

Other objects and advantages will hereinafter appear.

25 In the accompanying drawings,

Figure 1 is a part-sectional side elevation of an Underwood front strike writing machine provided with the present improvements.

30 Fig. 2 is a sectional elevation of part of the gear connection between the master-wheel of the computing mechanism and the devices by which said master-wheel is operated.

35 Fig. 3 is a rear elevation of the principal features of the computing mechanism seen at Fig. 1; the parts shown in normal positions.

40 Fig. 4 is a plan of the lower portion of the computing and typewriting devices.

Fig. 5 is a perspective view illustrating the releasing or feeding of the secondary escapement-wheel of the computing mechanism, from the position at Fig. 6.

45 Fig. 6 is a rear perspective view of the principal members of the mechanism which enables the paper carriage of the typewriter to release or feed the escapement wheel of the computing mechanism; and also of the 50 several key-locking devices.

Fig. 7 is a side elevation of the primary escapement wheel of the computing mechanism, showing also the cam which returns the escapement pins to normal positions.

55 Fig. 8 is a rear elevation showing a portion of the rack-and-pallet mechanism which enables the carriage to actuate the feeding devices of the computing mechanism; the pallet being shown depressed into engagement with a curved rack connected to the carriage.

Fig. 9 is a view illustrating the completion of the actuation, by the carriage, of the devices which feed or release the escapement-wheel of the computing mechanism.

Fig. 10 is a diagrammatic elevation of a set of interfering blades connected to the keys, one of said blades being shown in effective position, whereby it prevents the operation of the other blades, and hence of 70 the keys controlled thereby.

Typewriting mechanism.—The typewriting mechanism includes alphabet and character keys 1 and numeral keys 2, all mounted upon levers 3, having returning springs 4 and connected by means of elbow levers 5 with type-bars 6, to cause the latter to swing upon pivots 8 to the platen 7.

Each type-bar carries a heel 9, to press rearwardly a universal bar 10, mounted 80 upon a frame 11, the latter pivoted at its rear end to idle arms 12^a. Said universal bar frame 11 swings rearwardly a dog rocker 12 carrying a feeding dog 13 and a detent dog 14, whereby a paper-carriage 15 85 is given its letter-feeding motion, said carriage being propelled by a spring 15^a. Said dogs move into and out of engagement with an escapement wheel 16, which is connected to a pinion 17, the latter meshing with a 90 rack 18 upon said carriage. Upon the universal bar is provided an actuator 19 for a ribbon-vibrating lever 20. As so far described, the parts are in common use upon the Underwood typewriting machine.

95 Whenever a key is depressed, the elbow lever 5 is swung forwardly, and the type-bar is swung rearwardly against the platen to make an impression thereon, and the universal bar pushes the feeding-dog 13 out of engagement with the escapement wheel 16, and the detent dog 14 into engagement with said wheel; no letter-feeding motion of the carriage occurring at this time. Upon relieving the key from pressure, the parts are 100 returned to normal positions in the usual manner, the universal bar being returned by a spring 21, and moving the detent dog out of engagement with the escapement wheel 16, and the feeding-dog 13 into engagement therewith; said feeding-dog permitting the carriage to advance a letter space under the influence of the driving spring 15^a, as usual.

105 *Computing mechanism.*—All of said keys 115 control the letter-feeding movements of the carriage 15; but only the numeral keys 2 are connected to the computing mechanism, which is power-driven, its motor being indicated at 22, and being connected by a suitable train of gearing to the adding or dial wheels 23, and a primary escapement wheel 24, the latter being under the control of the numeral keys 2, whereby the keys are enabled to determine how far the computing 120 wheels 23 shall be rotated by the motor 22.

125 Preferably, the motor 22 is constantly revolving, although the primary escapement wheel 24 remains motionless, together with the computing wheels, until the keys 2 are 130

operated. The connection from the motor includes any suitable friction clutch 25, whereby is driven a shaft 26, the latter having a pinion 27 meshing with a pinion 28, whereby is rotated a shaft 29, having at its opposite end a pinion 30. To the last is connected, by means of a gear 31, a pinion 32 upon a shaft 33, the latter also having a pinion 34, which is connected by means of a pinion 35 to vertical shaft 36, the latter carrying a pinion 37, meshing with a pinion 38 fixed upon shaft 39, which carries a master-wheel 40, arranged interiorly of a series of computing wheels, in the shape of rings 41, having internal teeth 42 to engage the projecting master-wheel teeth. The computing wheels are supported upon a special carriage or frame 43, which is connected by arms or lugs 44 to the typewriter carriage 15, to travel therewith, whereby the computing wheels are given a denominational movement, relatively to the stationary master-wheel, at every letter-feeding movement of the main carriage 15.

For carrying tens from one computing wheel to the next, there may be employed any of the devices illustrated in any of my pending applications, or any other suitable tens-carrying devices. The wheels 41 mesh with gears on dial or number-bearing wheels 23.

The primary escapement wheel 24 is connected to the described train of gearing by means of pinion 45, on the shaft of the escapement wheel, said pinion meshing with gear 46 fixed to gear 31 already described. Said escapement wheel 24 carries a set of settable pins or teeth 47, one of which is projected and in engagement with a four-toothed pinion 48 (Fig. 6), which is connected to a secondary escapement wheel 49, the latter normally pressing against a feeding dog 50.

The movement of said dog 50 releases the secondary wheel 49, and allows the latter to be turned by the projecting escapement pin or tooth 47, so that the succeeding tooth of the four-toothed pinion 48 may be engaged by the next projected tooth 47, to arrest the primary escapement wheel 24, and hence the described train of gearing, including the computing wheels 41.

The escapement pins 47 are projected by means of the numeral keys 2, the latter being connected by links 51, pendent from bell-cranks 52 and having hooks 53 to engage suitable projections or parts 54 on the key levers 3. The bell cranks are connected by horizontal links 55 to arms 56, suitably pivoted at 57, and preferably formed at their opposite ends with cams 58, for camming the escapement pins 47 from normal positions to projected positions, to enable them to engage the four-toothed pinion 48. With the exception of the cams 58, the computing

mechanism details so far described, are set forth in certain of my said pending applications.

Carriage-operated escapement.—The dog 50 is operated at the letter-feeding movement of the paper carriage 15 of the type-writing machine. For this purpose, a rock shaft 59, on which said dog is fixed, is provided with an arm 60, connected by a link 61 to an upstanding lever 62, to which is pivoted at 63 a pallet 64 having a tooth 65 normally standing idly above a curved rack or toothed wheel 66. The latter is fixed to the shaft 67 which carries the escapement wheel 16 of the paper carriage 15, so that the two wheels 16, 66 revolve in unison, or as if constituting a single wheel.

It will be understood that during the ordinary operation of the paper carriage 15, the wheel 66 may revolve, but the pallet 64 lies idle as in Figs. 3 and 6. All of the numeral keys, however, have means to depress the pallet into engagement with the wheel 66, so that during the succeeding movement of the paper carriage, said pallet will be forced by the wheel 66 toward the right, from the position of Fig. 8 to that of Fig. 9 thereby vibrating the lever 62, and through the link 61 swinging the feeding dog 50 over to free the secondary escapement wheel 49, as at Figs. 5 and 9.

The movement of the pallet 64 is effected by any of the numeral keys 2 through the arms 56, said arms being normally adapted to engage a universal disk or member 68, around which the arms are grouped radially. Said disk is mounted upon a guide rod 69 and has a returning spring 70. Upon the rod 69 is provided a head or collar 71, and the end of a lever 72 is confined between said head and said universal bar or member 68 to be operated thereby. The lever is pivoted at 73 to any fixed support, and connected by a link 74 to an arm 75 of a bell crank 76, a second arm 77 thereon being connected by a link 78 to a lever 79, the latter having a pin 80 to engage said pallet 64 to depress the same.

Operation.—In the operation of the parts so far described, the keys 1 may be manipulated for ordinary typewriting in the manner already set forth. When a numeral key 2 is depressed, it also swings up its type-bar to print, and the type-bar operates the universal bar frame 11 of the letter-feeding mechanism, the rear of the latter engaging a projection 12^a on the dog rocker and moving the feeding-dog 13 out of engagement, and the detent dog 14 into engagement with the escapement wheel 16. At the same time the link 51 is pulled down by said key, and bell crank 52 is turned, and by means of the link 55 swings arm 56, thereby operating the universal member 68 and the lever 72, which, through the link 74, bell crank 76 and link 130

78, operates the lever 79. The pin 80 on the latter presses the pallet 64 down to the Fig. 8 position (against the tension of spring 81) and brings the tooth 65 into engagement with the teeth of the curved rack or wheel 66.

The downward movement of the pallet 64 is opposed by a V-shaped spring detent 82, which normally holds up a pin or projection 83 on the end of pallet 64, as seen at Figs. 3 and 6. This detent yields to the downward pressure of lever 79, and the projection 83 presses the detent aside, and descends to the Fig. 8 position, where it may 10 be held down by the same detent against the lifting tension of spring 81. During the depression of the key 2, there is no endwise movement of the pallet 64, and the dog 50 remains motionless, and continues to hold 15 the secondary escapement wheel 49 against movement, as well as the primary escapement wheel 24.

During the swinging of the arm 56 effected by the depression of the key 2, the 20 cam 58 on said arm engages the adjacent pin 47 on the main escapement wheel 24, and projects the same into position to engage the four-toothed pinion 48. No other movement of any part of the adding mechanism occurs upon the down stroke of the key; the adding wheels all remaining stationary upon such down stroke.

Upon the relief of the key 2 from pressure, the type bar and key lever are returned 25 to normal positions, together with arm 56, cam 58, universal member 68, and the parts connected to the latter, including the lever 79. Upon the return of the type bar from the platen, the spring 21 moves the universal 30 bar forwardly, and the detent dog 14 escapes from, and the feeding-dog 13 moves into line with the escapement wheel 16 of the carriage 15, and the spring 15^a is permitted to pull 35 said carriage one letter space.

The wheels 16 and 66 are accordingly 40 moved the distance of one tooth, and the pallet 64 is forced to the right from the position at Fig. 8 to the position at Fig. 9, the lever 62 being vibrated, and through the link 61, arm 60 and rock shaft 59 moving the feeding dog 50 to permit rotation of the secondary escapement wheel 49, by means of the projecting pin 47; the succeeding tooth of said pinion 48 being engaged by the pin 47 which was projected by the key 2 which has just been released, thus determining the extent of rotation of the power-driven primary escapement wheel 24 and hence of the master wheel 40 and of the computing wheel 41 with which the master wheel is at the time in engagement; a stationary cam 47^a (Fig. 7) returns the projected pins 47.

This release of the secondary escapement wheel 49 occurs at the final portion of the

letter-feeding movement of the paper carriage 15.

The succeeding tooth of the secondary escapement wheel 49 may be arrested by a detent dog 84, fixed to the feeding dog 50, and a little in rear thereof as in Fig. 1, to 70 give clearance to the wheel 49.

During the movement of the wheel 66 to the right from the position at Fig. 8 to that at Fig. 9, the pin 83 on the pallet rides along the under side of a point or trip 85, which is formed upon the bottom of a fixed bracket 86; the spring 81 tending constantly to lift said pin 83.

As soon as pallet 64 has been driven by the wheel 66 far enough to the right, at Fig. 80 9, the pin 83 is lifted by the spring 81 past the tip of the point 85, and the spring 87 at once draws the pallet 64 to the left, the pin 83 riding up along an inclined portion 88 of the point 85, whereby said projection 85 83 is lifted, and tooth 65 is brought up clear of the wheel 66; said spring 87 returning the parts to normal positions, including lever 62 and dogs 50 and 84, and the tooth of the secondary escapement wheel 49 slipping off from the detent 84, and resting in its normal position against the feeding dog 50. The spring 87 may be connected to an ear 89 formed on the pallet 64, and may be attached to a lug 90 provided upon the 95 frame of the typewriter; and the pallet 64 may have an adjustable stop 91 to engage said lug, so that said pallet shall be held in proper position for engagement with the teeth of wheel 66, as at Fig. 3; the adjustable stop 91 permitting the pallet 64 to accommodate any variation in the normal position of the teeth of the wheel 66.

The carriage 15 thus effects or controls the rotation of the computing master wheel 105 40, the relative denominational movement 45 between which and the computing wheels is also controlled by said carriage.

The links 51 (Fig. 6) which connect the 110 keys 2 to the bell crank 52 are passed through holes 92 in a horizontal bar 93. The latter may also be shifted endwise to the left (Fig. 3) to disconnect said links, so that the keys 2 may be operated without 115 actuating any part of the adding mechanism, and without causing the pallet 64 to move down into engagement with the wheel 66. Said bar 93 may be provided with a finger piece 94, and a detent 95 may hold the bar at either end of its movement. It 120 will thus be understood that the links 51 swing around points 96 at which they are pivoted to the bell cranks 52; their released positions being shown in dotted lines at Fig. 3.

The parts so far detailed are disclosed and 125 claimed in my application No. 554,452, filed April 9, 1910.

Means controlled by primary escapement wheel for locking the numeral keys.—It will be observed that the cam 58 is not effective until the final portion of the depression of a numeral key 2, so that the primary escapement wheel 24 has the interval between the arrest of the paper carriage 15 and the completion of the next down stroke of a numeral key in which to turn, this interval being usually sufficient for the purpose, even when the keys are manipulated rapidly. As a safeguard, however, a device is provided for preventing the operation of a numeral key during the rotation of said primary escapement wheel 24.

This safety device may comprise a link 100, having at one end an eye or slot 101 through which the lever 72 extends, and pivoted at the other end at 102 to an arm 103 formed upon a tumbler 104, which is pivoted loosely upon the rock shaft 59 which carries the dog 50, so that the tumbler and rock shaft may rotate independently of each other. Said rock shaft is movable endwise, and the tumbler 104 is confined between shoulders or collars 105 fixed upon the rock shaft, so as to partake of the longitudinal movement of the latter. A leaf spring 106, pressing against the end of the rock shaft, tends to move it to the right at Fig. 6; but this tendency is normally overcome by the pressure of the tooth of the secondary escapement wheel 49 upon the dog 50 fixed to said rock-shaft. The tumbler 104 is therefore normally held free from an abutment or stop pin 107 provided upon a fixed bracket 108, and hence the tumbler may swing idly during the strokes of the numeral keys 2.

Every time that the secondary escapement wheel 49 is released from the dog 50, however, the spring 106 snaps the shaft 59 to the right at Fig. 5, so that the tumbler 104 is brought beneath the abutment 107, thus preventing any numeral key from operating, since the abutment 107 arrests or locks against rotation the tumbler 104, and hence prevents movement of the link 100, the bar 72, the universal disk or member 68, all the arms 56, the links 55, bell cranks 52, the links 51 and the keys 2. This locking is effective until the primary escapement wheel 24 of the computing mechanism completes its rotation, and through the pinion 48 causes the succeeding tooth of the secondary escapement wheel 49 to press against the dog (84 or 50) to move the shaft 59 to the left at Fig. 6 against the tension of spring 106, thereby releasing the tumbler 104 from the stop 107, and hence permitting the operation of the train of devices connected to said tumbler through the link 100.

Alphabet-key lock.—To prevent any of the alphabet keys 1 from operating the car-

riage-feeding mechanism while the primary escapement wheel 24 of the computing mechanism is rotating, the link 100, extending from the tumbler 104, may be prolonged at 109 and formed at its end with an eye or slot 110, in which may be inserted the end 70 of a lever 111; the latter pivoted between its ends at 112 upon any suitable fixed support. Said lever 111 is shown pivoted at 113 at the other end to a link 114, the end of which is pivoted at 115 to a bell crank 116, pivoted at 117 upon a fixed support.

To this bell crank is pivoted at 118 the upper end of a pendent link 119, having at its lower end a hook 120 to engage under an arm 121. This arm is mounted loosely upon 80 a rock shaft 122, (upon which latter are fixed the forwardly extending levers 123 bearing the usual word-spacing key 124 at the front of the keyboard). This arm 121 forms one of a pair, the other member of 85 the pair being designated as 125, and both being loosely pivoted upon said rock shaft 122, and being rigidly connected by a bar 126 close to said shaft 122. At their forward ends said arms 121, 125 support a horizontal 90 bar or rod 127, extending across the machine in front of the keys 2 and directly beneath those key levers 3 which bear the alphabet keys 1. The rod 127 is fixed to the arms 121, 125. These parts, taken together 95 with the bar 126, form a rigid frame, which may be swung down about the pivot 122 by depression of any of the alphabet keys 1, as will be understood from inspection of Fig. 1; said frame having a returning spring 100 127.

It will be understood from the foregoing that unless the tumbler 104 is free from the fixed pin or abutment 107, the link 100, 109 cannot be moved, and hence through the 105 members 111, 114, 116, 119, 121 and 127, the alphabet and character keys 1 are prevented from being depressed during the rotation of the primary escapement wheel 24 of the adding mechanism.

It will also be understood that the engagement of the succeeding tooth 49 of the secondary escapement wheel with the dog 84 or 50 will move the shaft 59 endwise and release the tumbler 104 from the stop 107, 115 thus permitting the link 100, 109 to be moved endwise again, and hence permitting any alphabet or character key to be depressed. In this manner, re-operation of the carriage-feeding devices 11, 13, 14, is prevented while 120 the primary escapement wheel 24 is turning, and while the master wheel 40 is rotating one of the computing wheels 41, and hence there is no liability of relative movement in axial direction occurring between the 125 master wheel and the computing wheels during such rotation, so that liability of error is avoided.

Space-key lock.—In order also to prevent the space key 124 from operating the carriage-feeding devices during the rotation of said primary escapement wheel 24 of the computing mechanism, I hang from said rod 127 a pair of links 128, carrying lugs 129 which project beneath said levers 123 of the space key. It will be understood that the effect or purpose of these lugs 129 with respect to the space key is similar to that of the bar 127 with respect to the alphabet keys 1; and hence that the space key cannot be depressed to operate the carriage-feeding devices, until the tumbler 104 is released by the escapement wheel 24. As is usual in the Underwood machine, the rock shaft 122 of the space key is provided with an arm 130, to operate an arm 131 extending forwardly and downwardly from the idle arms 12*. 20 *Tabulating key lock.*—Said Underwood machine is also frequently provided with a tabulating mechanism, comprising depressible keys 132 upon the forward ends of levers 133, which are fulcrumed at 134 between their ends and articulated at their rear ends at 135 to upstanding thrust-rods 136, which carry at their upper ends denomination stops 137, to engage column stops 138 carried upon a rack 139 which is usually secured to the paper carriage 15. Said thrust rods 136 are adapted to cause a movement of the paper carriage 15; lugs or shoulders 140 on said thrust rods 136 engaging a short universal bar 141, which is supported by an arm or arms 142 upon a rock shaft 143, the latter having an arm 144 connected by a link 145 to a lever 146, having a roll 147 to engage and lift the letter-feeding rack 18 upon the carriage 15. 30 In order to prevent depression of a tabulator key 132, and hence a movement of the carriage 15, during the rotation of the primary escapement wheel 24, the links 128 may be extended downwardly at 148, and carry at their lower ends a horizontal rod or bar 149 extending across the machine beneath the tabulating key levers 133. The bar 149 is, of course, controlled by the tumbler 104 in the manner already described respecting the bar 127 and lugs 129. Thus it will be seen that no movement of any of the carriage controlling devices can occur if the power-driven computing mechanism is rotating. 40 To summarize, it will be seen that besides feeding the carriage, the principal function of the type-operating numeral keys 2 is to set the escapement pins 47 for determining the extent of rotation of the computing devices, and that upon the carriage itself depends not only the relative denominational movement between the master wheel 40 and the computing wheels 41, but also the actual rotation of said wheels, and that further operation of the carriage-feeding or spacing 50 devices cannot occur until completion of the rotation of the power-driven computing wheels, which are released by the movement of the carriage, and hence the movements of all the parts are bound to take place in 70 proper sequence.

Means for enabling each numeral key to interfere with the operation of the other numeral keys.—Each of the key-operated arms 56 may be provided with an interference member, preferably a blade 150, which may be in the form of a segment having the pivot 57 as a center; the pin-setting cam 58 being formed upon the outer portion of said blade. These blades 150 (which are carried 75 upon the ends of extensions 151 of said arms 56) are loosely guided in a series of radial slots 152 formed in a support 153; and the tips of the blades occupy a row which forms the principal portion of a circle, around a 80 small central opening 154 in said support 153.

So long as the opening 154 (Fig. 10) is occupied by a blade, no other blade can pass through said opening, as it will encounter 90 the first blade, and hence it will be impossible to operate any of the remaining figure keys until the first key is returned to or substantially to normal position. Thus, each numeral key 2 interferes with the operation 95 of all the other numeral keys, so that it is not practicable to depress more than one numeral key at a time; and as soon as one numeral key is partly depressed, the depression of any other numeral key is prevented. 100

Means for causing interference between each numeral key and the alphabet and other keys.—The link 114 is extended from 155 to connect at 156 with an arm 157 having an extension 158, the latter carrying an interfering blade 159 guided in one of the slots 152: said arm 157 corresponding in construction and operation throughout with the arms 56, except that it has no cam 58 for setting the pins 47, nor does it operate 110 the universal disk, or member 68, the latter being accordingly cut away as shown. It will be seen that whenever the frame 121, 125, 126, 127 is depressed, the link 119 is pulled down, the bell crank 116 is rocked, 115 the link 114, 155 is pulled, the arm 157 turned, and the blade 159 caused to enter the small central opening 154 in the fixture 153, thereby preventing the entrance of any of the blades 150, so that none of the numeral 120 keys 2 can be depressed.

Thus there is prevented not only the operation of a numeral key prematurely after the depression of the space key or an alphabet key, but also the depression of a numeral 125 key simultaneously with a tabulator key. The operator is liable to depress a tabulator key, and after holding it down an instant, to depress a numeral key before the paper carriage has completed its tabulating run, 130

and before releasing the tabulator key. It will be seen that by this invention the depression of any of the carriage-controlling keys 1, 124 or 132, moves the interfering 5 blade 159 into position to prevent operation of any numeral keys.

This invention, of course, prevents the simultaneous downward movement of a numeral key and any of the other keys 1, 124 10 or 132, since the blade 159 cannot enter the central opening 154 at the same time with any of the blades 150.

It also prevents the operation of any of the keys 1, 124 or 132 while a numeral key 15 is depressed; since when the central opening 154 is occupied by any blade 150, the blade 159 cannot enter said opening, but will collide with said blade 150.

It will thus be seen that the frame or 20 member 121, 125, 126, 127, which is operated by all of the alphabet keys 1, the space key 124 and the tabulator keys 132, not only serves to lock all of said keys against actuation during the rotation of the primary 25 escapement wheel 24 of the computing mechanism, but also, by being connected to the additional interference blade 159, prevents premature operation of any of said keys with respect to any of the adding keys, or 30 vice versa.

The slot 101 is of sufficient length to permit the actuation of the tumbler 104 by the frame 121, etc., without operating the lever 72 which extends through said slot; and the 35 slot 110 is of sufficient length to permit said lever 72 to operate the rod 100, 109 to swing the tumbler 104 without operating the lever 111.

Key check.—Each of the bell cranks 52 40 (one of these being provided for each numeral key) is preferably provided (as set forth in application No. 543,603, filed February 12, 1910, by Walter Wright and Gustave O. Degener and patented August 14, 45 1917, No. 1,237,008,) with a segmental ratchet 160 (Fig. 3), and pivoted upon the ratchet (Fig. 3), and pivoted upon the frame of the machine at 161 is a pawl 162 to engage the teeth of said ratchet in a manner 50 to prevent premature reversal of the associated key. When the key starts to move down, the pawl engages the ratchet and prevents return movement of the key, so that it becomes necessary to press the key down 55 to the limit of its movement, whereupon the ratchet will clear the pawl, and the latter will be swung by its spring 163 into position to reengage the ratchet on the upward stroke of the key, and prevent another down 60 stroke thereof before the key returns to normal position.

From this construction, it results that the operation of any numeral key must be completed before any alphabet key can be operated, since the interfering blade 150 which

is associated with the depressed numeral key cannot return to normal position ahead of said key, and hence none of the alphabet keys can be operated in the meantime.

If desired, the bell crank 116 can also be 70 provided with a similar ratchet to coöperate with a similar pawl, this being particularly useful in connection with the tabulator keys, to insure that the down stroke of the tabulator key shall be finished, and also that it 75 shall return to normal position before being reoperated. This will prevent liability of a computing numeral key being operated during a partial operation of the tabulating mechanism, or a false movement of any of 80 the tabulating parts or of the carriage.

Key disconnection.—When the handle 94 is operated to carry the bar 93 to the left at Fig. 3, thereby disconnecting the type-operating numeral keys from the computing 85 mechanism (through the engagement of said bar with the links 51), the link 119 is also swung to the left to the dotted-line position seen at Fig. 3, thereby disconnecting the crank 116 from the arm 121, so that the alphabet keys, the space key and the tabulator 90 keys can no longer be locked; although of course it will be understood that the usual line-locking mechanism (not shown) will still be effective to lock the keys at the end 95 of every line of writing.

Variations may be resorted to within the scope of the invention, and portions of the improvement may be used without others.

Having thus described my invention, I 100 claim:

1. The combination of a power-driven computing mechanism having an escapement wheel, a carriage, said computing mechanism including a member connected to have 105 a denominational step-by-step movement at the feeding movement of the carriage; a set of numeral keys; means to lock the keys against operation; a carriage-feeding device controlled by said keys, a dog device restraining said escapement wheel; means controlled by the carriage at its letter-feeding movement to operate said dog device to release said escapement wheel; and mechanism extending from said keys to said escapement 110 wheel, to determine the extent of movement of the latter; said dog device being movable by the pressure of said escapement wheel; and having means effective at such movement to release said keys. 115

2. In a combined typewriting and computing machine, the combination of a power-driven computing mechanism having an escapement wheel, a carriage, type-operating keys including a set of numeral keys, a 125 carriage-feeding device controlled by all of said keys, said computing mechanism including a member connected to have a denominational step-by-step movement at the feeding movement of the carriage, normally 130

ineffective means operated by the carriage at its letter-feeding movement to initiate a movement of said escapement wheel, means controlled by said numeral keys to render 5 said last mentioned means effective, mechanism extending from said numeral keys to said escapement wheel to determine the extent of movement of the latter, and means normally held released by said escapement 10 wheel, but rendered effective during the rotation thereof, for preventing operation of said keys.

3. In a combined typewriting and computing machine the combination of a power-driven computing mechanism having an escapement wheel, a dog device to release and arrest said escapement wheel, a carriage, alphabetical and numeral type-operating keys, a carriage-feeding device controlled by all 15 of said keys, said computing mechanism including a member connected to have a denominational step-by-step movement at the feeding movement of the carriage, normally ineffective means operated by said carriage 20 at its step-by-step movement to initiate a movement of said escapement wheel, means controlled by said numeral keys to render said last-mentioned means effective, mechanism extending from said numeral keys to 25 said escapement wheel to determine the extent of escapement of the latter, and means to lock both said numeral and alphabet keys against operation; said key-locking means normally held released by the pressure of 30 said escapement wheel upon said dog device, and including a spring to displace said dog device and lock the keys when the dog device releases the escapement wheel.

4. In a combined typewriting and computing machine, the combination of a power-driven computing mechanism having an escapement wheel, a dog device to release and arrest said escapement wheel, a carriage, alphabetical and numeral type-operating keys, 40 a carriage-feeding device controlled by all of said keys, normally ineffective means operated by said carriage at its step-by-step movement to initiate a movement of said escapement wheel, means controlled by said 45 numeral keys to render said last-mentioned means effective, means also controlled by said numeral keys to determine the extent of movement of said escapement wheel, a spring to displace said dog device when the 50 latter releases said escapement wheel under the control of said carriage, a tumbler also displaceable by said spring, an abutment to be engaged by the displaced tumbler to lock the latter, and means connecting both 55 the alphabet and numeral keys to said tumbler to lock said keys.

5. The combination of a step-by-step feeding carriage, a rack connected thereto, a pallet normally out of engagement with 60 said rack, a set of numeral keys having 65

means to control said carriage, a universal bar or disk operable by said numeral keys, a device operated by said universal bar to set said pallet into engagement with said rack to be operated thereby, a dog device 70 operable by said pallet, means to return the pallet to normal position together with said dog device, a computing mechanism including a member connected to said carriage to have a denominational movement, means, 75 including an escapement wheel, controlled by said dog device to release and stop said computing mechanism, means controlled by said keys to determine the extent of movement of said computing mechanism, a tumbler connected to said universal bar to be operated idly thereby, a spring having means to displace said dog device and said tumbler when the dog device releases the escapement wheel, and an abutment engaged 80 by the displaced tumbler to prevent operation of the latter, the dog device and tumbler being returnable to normal positions by pressure of said escapement wheel.

6. The combination of a computing mechanism including a power-driven escapement wheel provided with settable escapement teeth, keys having means to set said teeth, a feeding dog normally restraining said escapement wheel, a detent dog normally disengaged from said wheel, a step-by-step feeding carriage controlled by said keys, said computing mechanism including a member connected to said carriage to have a denominational movement, and means, including a rock shaft whereon said dogs are mounted, controlled by said carriage to operate said shaft and thereby said feeding dog to release said escapement wheel, means to return said shaft and thereby said feeding dog to again restrain said escapement, a spring to displace said rock-shaft endwise when the escapement wheel escapes from the feeding dog, a tumbler displaceable with said rock shaft, an abutment engaged by the displaced tumbler to prevent operation of the latter; the rock-shaft and tumbler being returnable to normal positions by pressure of said escapement wheel upon the feeding dog; said tumbler being loosely mounted 100 upon said rock shaft and confined between collars or shoulders thereon, and connections between said numeral keys and said tumbler to lock said keys during movement of said escapement wheel.

7. In a combined typewriting and adding machine, the combination of numeral keys, type-operating alphabet keys, a step-by-step feeding carriage controlled by all of said keys, a power-driven computing mechanism including a member which has a denominational step-by-step movement concomitantly with the carriage, said computing mechanism having an escapement wheel 115 the extent of whose rotation is controlled 120

- by said numeral keys, means dependent upon the operation of the numeral keys and the movement of the carriage for releasing said escapement wheel, a tumbler connected to 5 said alphabet keys to be moved thereby, an abutment, said tumbler being normally held by said escapement wheel out of engagement with said abutment, and means to move said tumbler into engagement with 10 said abutment to lock said alphabet keys upon the release of said escapement wheel, to thereby prevent printing by an alphabet key during computation.
8. In a combined typewriting and adding machine, the combination of type-operating numeral keys, type-operating alphabet keys, a step-by-step feeding carriage controlled by all of said keys, a power-driven computing mechanism including a member which 15 has a denominational step-by-step movement concomitantly with the carriage, said computing mechanism having an escapement wheel the extent of whose rotation is controlled by said numeral keys, means dependent upon the operation of the numeral keys for releasing said escapement wheel, a tumbler connected to all of said keys to be moved thereby, an abutment, said tumbler being normally held by said escapement 20 wheel out of engagement with said abutment, and a spring to move said tumbler into engagement with said abutment to lock all of said keys upon the release of said escapement wheel.
- 30 9. In a combined typewriting and adding machine, the combination of type-operating numeral keys, type-operating alphabet keys, a step-by-step feeding carriage controlled by all of said keys, a power-driven computing mechanism including a member which has a denominational step-by-step movement concomitantly with the carriage, said computing mechanism having an escapement wheel the extent of whose rotation is controlled by said numeral keys, means dependent upon the operation of the 35 numeral keys for releasing said escapement wheel, a bar mounted to be moved by said alphabet keys at every depression of the latter, means for locking said bar against movement to prevent operation of the keys, a tumbler connected to said bar, an abutment, said tumbler being normally held by said escapement wheel out of engagement with said abutment, a spring to move said 40 tumbler into engagement with said abutment upon the release of said escapement wheel to lock said alphabet keys, and a universal bar or device independent of said alphabet keys and operable by any of said numeral keys and operatively connected to said tumbler to coöperate therewith, to lock and release said numeral keys also.
- 45 10. In a combined typewriting and adding machine, the combination of type-operating numeral keys, type-operating alphabet keys, a step-by-step feeding carriage controlled by all of said keys, a power-driven computing mechanism including a member which has a denominational step-by-step movement concomitantly with the 50 carriage, said computing mechanism having an escapement wheel the extent of whose rotation is controlled by said numeral keys, means for locking said bar against movement, to prevent operation of the keys, and means controlled by said escapement wheel to hold said locking means normally in released position.
- 55 11. In a combined typewriting and adding machine, the combination of type-operating numeral keys, type-operating alphabet keys, a step-by-step feeding carriage controlled by all of said keys, a power-driven computing mechanism including a member which has a denominational step-by-step movement concomitantly with the carriage, said computing mechanism having an escapement wheel the extent of whose rotation is controlled by said numeral keys, means dependent upon the operation of the 60 numeral keys for releasing said escapement wheel, a bar mounted to be moved by said alphabet keys at every depression of the latter, means for locking said bar against movement to prevent operation of the keys, a tumbler connected to said bar, an abutment, said tumbler being normally held by said escapement wheel out of engagement with said abutment, and a spring to move said tumbler into engagement with said abutment upon the release of said escapement wheel to lock said alphabet keys, and a universal bar or device independent of said alphabet keys and operable by any of said numeral keys and operatively connected to said tumbler to coöperate therewith, to lock and release said numeral keys also.
- 65 12. In a combined typewriting and adding machine, the combination of type-controlling numeral keys, type-controlling alphabet keys, a step-by-step feeding carriage controlled by all of said keys, a power-driven computing mechanism including a member which has a denominational step-by-step movement concomitantly with the carriage, said computing mechanism having an escapement wheel the extent of whose rotation is controlled by said numeral keys, a dog device for releasing and stopping said escapement wheel, means dependent upon the operation of the numeral keys for operating said dog device, a tumbler, means to displace said dog device and said tumbler upon the release of the escapement wheel by the dog device, an abutment engaged by the displaced tumbler to lock the latter against operation, and means associated with the locked tumbler to prevent operation of all of said keys; said dog device and tumbler being returnable to normal positions by said

escapement wheel upon the arrest of the latter.

13. In a combined typewriting and adding machine, the combination of type-controlling numeral keys, type-controlling alphabet keys, a step-by-step feeding carriage controlled by all of said keys, a power-driven computing mechanism including a member which has a denominational step-by-step movement concomitantly with the carriage, said computing mechanism having an escapement wheel the extent of whose rotation is controlled by said numeral keys, a dog device for releasing and stopping said escapement wheel, means dependent upon the operation of the numeral keys and also controlled by said carriage for operating said dog device, a tumbler, means to displace said dog device and said tumbler upon the release of the escapement wheel by the dog device, means engaged by the displaced tumbler to lock the latter against operation, and means associated with the locked tumbler to prevent operation of said alphabet keys; said dog device and tumbler being returnable to normal positions by said escapement wheel upon the arrest of the latter.

14. In a combined typewriting and computing machine, the combination of a power-driven computing mechanism having an escapement wheel, a carriage, said computing mechanism including a member connected to have a denominational step-by-step movement at the feeding movement of the carriage; a set of type-controlling numeral keys; a set of type-controlling alphabet keys; means to lock all of said keys against operation; a carriage feeding device controlled by said keys; a dog device restraining said escapement wheel; means operable by the carriage at its letter feeding movement to operate said dog device to release said escapement wheel; and mechanism extending from said numeral keys to said escapement wheel, to determine the extent of movement of the latter; said dog device being movable by the pressure of said escapement wheel; and having means effective at such movement to release all of said keys.

15. In a combined typewriting and computing machine, the combination of a power-driven computing mechanism having an escapement wheel, a carriage, said computing mechanism including a member to move step-by-step at the feeding movement of the carriage, normally ineffective means operable by said carriage and extending to said escapement wheel to release the latter, a set of numeral keys, carriage-feeding devices controlled by said keys, means to enable any of said keys to render effective at the letter feeding movement of the carriage, the devices which extend from said carriage to said escapement wheel, whereby the escapement wheel is released, mechanism extend-

ing from said keys to said escapement wheel to determine the extent of movement of the latter, a set of type-controlling alphabet keys having means to control said carriage, and means normally held released by said escapement wheel, but rendered effective during the rotation thereof, for preventing operation of said alphabet keys.

16. In a combined typewriting and computing machine, the combination of a power-driven computing mechanism having an escapement wheel; a dog device to release and arrest said escapement wheel, a carriage, alphabetical and numeral type-controlling keys, a carriage feeding device controlled by all of said keys, said computing mechanism including a member connected to have a denominational step-by-step movement at the feeding movement of the carriage, a rack connected to said carriage, a pallet, means to enable said numeral keys to move said pallet into engagement with said rack to be operated thereby, an operative connection between said pallet and said dog device, mechanism extending from said numeral keys to said escapement wheel to determine the extent of escapement of the latter, and means to lock said keys against operation; said key-locking means normally held released by the pressure of said escapement wheel upon said dog device, and including a spring to displace said dog device and lock the keys when the dog device is operated by said pallet to release the escapement wheel, and also including a locking and releasing bar mounted to be moved by all of said alphabet keys.

17. The combination of type-controlling alphabet keys, a computing mechanism including a power-driven escapement wheel provided with settable escapement teeth, type-controlling numeral keys having means to set said teeth, a feeding dog normally restraining said escapement wheel, a detent dog normally disengaged from said wheel, a step-by-step feeding carriage controlled by all of said keys, said computing mechanism including a member connected to said carriage to have a denominational movement, means, including a rock shaft whereon said dogs are mounted, operable by said carriage to operate said feeding dog to release said escapement wheel, a spring to displace said rock-shaft endwise when the escapement wheel escapes from the feeding dog, a tumbler displaceable with said rock shaft, an abutment engaged by the displaced tumbler to prevent operation of the latter; the rock shaft and tumbler being returnable to normal positions by pressure of said escapement wheel upon the dog; and a bar movable by said alphabet keys and connected to said tumbler to be locked thereby.

18. In a combined typewriting and adding machine, the combination of numeral

- keys, type-operating alphabet keys, a space key, a step-by-step feeding carriage controlled by all of said keys, a power-driven computing mechanism including a member which has a denominational step-by-step movement concomitantly with the carriage, said computing mechanism having an escapement wheel the extent of whose rotation is controlled by said numeral keys, means dependent upon the operation of the numeral keys for releasing said escapement wheel, a member mounted to be operated by said alphabet keys and said space key, means for locking said member against movement to prevent operation of the alphabet and space keys, a tumbler connected to said member, an abutment, said tumbler being normally held by said escapement wheel out of engagement with said abutment, and a spring to move said tumbler into engagement with said abutment upon the release of said escapement wheel to lock said alphabet and space keys.
19. In a combined typewriting and adding machine, the combination of numeral keys, type-operating alphabet keys, a step-by-step feeding carriage controlled by all of said keys, tabulating keys for said carriage, a power-driven computing mechanism including a member which has a denominational step-by-step movement concomitantly with the carriage, said computing mechanism having an escapement wheel the extent of whose rotation is controlled by said numeral keys, means dependent upon the operation of the numeral keys for releasing said escapement wheel, a member mounted to be operated by said alphabet keys and said tabulating keys, means for locking said member against movement to prevent operation of the alphabet and tabulating keys, a tumbler connected to said member, an abutment, said tumbler being normally held by said escapement wheel free from control of said abutment, and means to cause said abutment to control said tumbler upon the release of said escapement wheel, to lock said alphabet and tabulating keys.
20. In a combined typewriting and adding machine, the combination of numeral keys, a step-by-step feeding carriage controlled by said keys, tabulating keys for said carriage, a power-driven computing mechanism including a member which has a denominational step-by-step movement concomitantly with the carriage, said computing mechanism having an escapement wheel the extent of whose rotation is controlled by said numeral keys; means dependent upon the operation of the numeral keys for releasing said escapement wheel, a member mounted to be operated by said tabulating keys, means for locking said member against movement to prevent operation of the tabulating keys, a tumbler connected to said member, an abutment, said tumbler being normally held by said escapement wheel, a member mounted to be operated by said alphabet keys and said space key, means for locking said member against movement to prevent operation of the alphabet and space keys, a tumbler connected to said member, an abutment, said tumbler being normally held by said escapement wheel out of engagement with said abutment, and a spring to move said tumbler into engagement with said abutment upon the release of said escapement wheel to lock said alphabet and space keys.
21. In a combined typewriting and adding machine, the combination of type-operating numeral keys, type-operating alphabet keys, a space key, a step-by-step feeding carriage controlled by all of said keys, tabulating keys for said carriage, a power-driven computing mechanism including a member which has a denominational step-by-step movement concomitantly with the carriage, said computing mechanism having an escapement wheel the extent of whose rotation is controlled by said numeral keys, means dependent upon the operation of the numeral keys for releasing said escapement wheel, a member mounted to be operated by said alphabet keys, said space key and said tabulating keys, means for locking said member against movement to prevent operation of the alphabet, space and tabulating keys, a tumbler connected to said member, and means to obstruct or lock said tumbler upon the release of said escapement wheel, to thereby lock said alphabet and space keys; means being controlled by said escapement wheel to hold said tumbler normally free of said obstructing means.
22. In a combined typewriting and computing machine, the combination of a step-by-step feeding carriage, a power-driven rotary computing mechanism including a member which has a denominational step-by-step movement concomitantly with the carriage, a set of numeral keys, a set of type-operating alphabet keys, means controlled by any of said keys to cause the carriage to feed, means controlled by the numeral keys to enable the carriage to cause the computing mechanism to rotate, means controlled by said numeral keys to determine the extent of rotation of the computing mechanism, and means to prevent the operation of the alphabet and numeral keys during the rotation of the computing mechanism.
23. In a combined typewriting and computing machine, the combination of a step-by-step feeding carriage, a power-driven rotary computing mechanism including a member which has a denominational step-by-step movement concomitantly with the carriage, a set of numeral keys, a set of type-operating alphabet keys, a space key, means controlled by any of said keys to cause the carriage to feed, means controlled by the numeral keys conjointly with the carriage to release or feed the computing mechanism, means controlled by said numeral keys to determine the extent of rotation of the computing mechanism.

member, an abutment, said tumbler being normally held by said escapement wheel out of engagement with said abutment, and means to move said tumbler into engagement with said abutment upon the release of said escapement wheel to lock said tabulating keys.

21. In a combined typewriting and adding machine, the combination of type-operating numeral keys, type-operating alphabet keys, a space key, a step-by-step feeding carriage controlled by all of said keys, tabulating keys for said carriage, a power-driven computing mechanism including a member which has a denominational step-by-step movement concomitantly with the carriage, said computing mechanism having an escapement wheel the extent of whose rotation is controlled by said numeral keys, means dependent upon the operation of the numeral keys for releasing said escapement wheel, a member mounted to be operated by said alphabet keys, said space key and said tabulating keys, means for locking said member against movement to prevent operation of the alphabet, space and tabulating keys, a tumbler connected to said member, and means to obstruct or lock said tumbler upon the release of said escapement wheel, to thereby lock said alphabet and space keys; means being controlled by said escapement wheel to hold said tumbler normally free of said obstructing means.

22. In a combined typewriting and computing machine, the combination of a step-by-step feeding carriage, a power-driven rotary computing mechanism including a member which has a denominational step-by-step movement concomitantly with the carriage, a set of numeral keys, a set of type-operating alphabet keys, means controlled by any of said keys to cause the carriage to feed, means controlled by the numeral keys to enable the carriage to cause the computing mechanism to rotate, means controlled by said numeral keys to determine the extent of rotation of the computing mechanism, and means to prevent the operation of the alphabet and numeral keys during the rotation of the computing mechanism.

23. In a combined typewriting and computing machine, the combination of a step-by-step feeding carriage, a power-driven rotary computing mechanism including a member which has a denominational step-by-step movement concomitantly with the carriage, a set of numeral keys, a set of type-operating alphabet keys, a space key, means controlled by any of said keys to cause the carriage to feed, means controlled by the numeral keys conjointly with the carriage to release or feed the computing mechanism, means controlled by said numeral keys to determine the extent of rotation of the computing mechanism.

computing mechanism, and means to prevent the operation of the alphabet keys, the numeral keys and the space key during the rotation of the computing mechanism.

24. The combination of a step-by-step feeding carriage, a power-driven rotary computing mechanism including a member which has a denominational step-by-step movement concomitantly with the carriage, a set of numeral keys, means controlled by any of said keys to cause the carriage to feed, tabulating keys for said carriage, means controlled by the numeral keys conjointly with the carriage to release or feed the computing mechanism, means controlled by said numeral keys to determine the extent of rotation of the computing mechanism, and means to prevent the operation of the numeral keys and the tabulating keys during the rotation of the computing mechanism.

25. In a combined typewriting and computing machine, the combination of a step-by-step feeding carriage, a power-driven rotary computing mechanism including a member which has a denominational step-by-step movement concomitantly with the carriage, a set of numeral keys, a set of type-operating alphabet keys, means controlled by any of said keys to cause the carriage to feed, tabulating keys for said carriage, means controlled by the numeral keys conjointly with the carriage to release or feed the computing mechanism, means controlled by said numeral keys to determine the extent of rotation of the computing mechanism and means to prevent the operation of the alphabet keys, the numeral keys and the tabulating keys during the rotation of the computing mechanism.

26. In a combined typewriting and computing machine, the combination of a step-by-step feeding carriage, a power-driven rotary computing mechanism including a member which has a denominational step-by-step movement concomitantly with the carriage, a set of numeral keys, a set of type-operating alphabet keys, a space key, means controlled by any of said keys to cause the carriage to feed, tabulating keys for said carriage, means controlled by the numeral keys conjointly with the carriage to release or feed the computing mechanism, means controlled by said numeral keys to determine the extent of rotation of the computing mechanism, and means to prevent the operation of the alphabet keys, the numeral keys, the space key and the tabulating keys during the rotation of the computing mechanism.

27. In a combined typewriting and adding machine, the combination of a step-by-step feeding carriage, keys to feed said car-

riage, said keys including type-operating numeral keys and type-operating alphabet keys, a power-driven computing mechanism including a member which has a denominational step-by-step movement concomitantly with the carriage, said computing mechanism having an escapement wheel the extent of whose rotation is controlled by said numeral keys, means dependent upon the operation of the numeral keys for releasing or feeding said escapement wheel, a bar mounted to be moved by said alphabet keys at every depression of the latter, means for locking said bar against movement to prevent operation of the keys, means controlled by said escapement wheel to hold said locking means normally released, and means also co-operating with said bar to prevent concomitant operation of any numeral key and any of the alphabet keys.

28. In a combined typewriting and adding machine, the combination of a step-by-step feeding carriage, keys to feed said carriage, said keys including type-operating numeral keys and type-operating alphabet keys, a power-driven computing mechanism including a member which has a denominational step-by-step movement concomitantly with the carriage, said computing mechanism having an escapement wheel the extent of whose rotation is controlled by said numeral keys, means dependent upon the operation of the numeral keys for releasing or feeding said escapement wheel, a bar mounted to be moved by said alphabet keys at every depression of the latter, means for locking said bar against movement to prevent operation of the keys, means controlled by said escapement wheel to hold said locking means normally released, a set of blades connected to said numeral keys, and a blade connected to said bar; all of said blades movable by their keys to a position common to all of the blades, so that when one blade occupies such common position, the other blades are prevented from operating, where-by their keys are locked.

29. In a combined typewriting and adding machine, the combination of a step-by-step feeding carriage, keys to feed said carriage, said keys including type-operating numeral keys and type-operating alphabet keys, a power-driven computing mechanism including a member which has a denominational step-by-step movement concomitantly with the carriage, said computing mechanism having an escapement wheel the extent of whose rotation is controlled by said numeral keys, means dependent upon the operation of the numeral keys for releasing or feeding said escapement wheel, a bar mounted to be moved by said alphabet keys at every depression of the latter, means for locking said bar against movement to pre-

- vent operation of the keys, means controlled by said escapement wheel to hold said locking means normally released, a set of blades connected to said numeral keys and a blade 5 connected to said bar; all of said blades movable by their keys to a position common to all of the blades, so that when one blade occupies such common position, the other blades are prevented from operating, where- 10 by their keys are locked, and means being provided for disconnecting said numeral keys at will from the computing devices and concomitantly disconnecting said bar from said locking means and said blades.
- 15 30. In a combined typewriting and computing machine, the combination with a key for operating type, of a traveling carriage, a tabulator key for arresting said carriage, a computing mechanism, an escapement 20 therefor controlled by said carriage through said type key, and means for preventing the operation of said tabulator key until the operation of said escapement has been completed.
- 25 31. In a combined typewriting and computing machine, the combination with a key for operating type, of a traveling carriage, an escapement for said carriage, a tabulator key, means controlled by said tabulator key 30 for operating said escapement and arresting said carriage, computing mechanism, an escapement therefor controlled by said carriage escapement, and means for preventing said tabulator key from operating said carriage escapement until the escapement of said computing mechanism has completed its movement.
32. In a combined typewriting and computing machine, the combination with a 40 traveling carriage, an escapement therefor, type-operating keys, and a space key controlling step-by-step movements of said carriage through said escapement, of computing mechanism, an escapement therefor controlled by said carriage through said type-operating keys, and means for preventing operation of said space key to control said carriage escapement until the escapement of said computing mechanism has completed 45 its movement.
33. The combination with a traveling carriage, of a computing mechanism, a series of numeral keys connected to control movements of said carriage and also connected to 50 control the action of said computing mechanism to accord with the numeral keys struck, alphabet keys, type actions operated by said alphabet keys, means for delaying the action of said computing mechanism initiated by the striking of a numeral key until 55 the concomitant movement of the carriage initiated at the same period by the same numeral key has been completed, and means for preventing the subsequent actuation of any alphabet key or of the same or any other 60 numeral key until the computing action initiated and started after the finish of the traveling movement of the carriage has itself been completed.
34. The combination with a traveling carriage, of a computing mechanism, a series of keys including numeral keys for controlling step-by-step movements of said carriage, said numeral keys being connected to said computing mechanism to control the action 70 thereof to correspond with the numeral keys struck, tabulating keys for controlling jump movements of said carriage, means for delaying the action of said computing mechanism initiated by the striking of a numeral 75 key until the movement of the carriage initiated by the same striking of the same numeral key has been completed, and means for preventing the actuation of said tabulating keys until the computation starting 80 after the finish of the traveling movement of the carriage has itself been completed.
35. The combination with a traveling carriage, of a computing mechanism, a series of keys including a set of numeral keys, said 85 numeral keys being connected to control movements of said carriage and actions of said computing mechanism, the latter to accord with the numeral keys actuated, locking elements connected to said numeral keys 90 to prevent the concomitant actuation of more than one numeral key, normally ineffective means for controlling the action of said computing mechanism from said carriage, shifting mechanism operated by said 95 locking elements for rendering said last-mentioned means effective, and a locking element operated by certain of said keys other than said numeral keys to coöperate with said other locking elements to interfere with 100 the action of said numeral keys, said last-mentioned locking element moving free and clear of said shifting mechanism so as to cause a locking action independent of a controlling action of said computing mecha- 105 nism on the part of said carriage.
36. The combination with a traveling carriage, of a computing mechanism, a series of keys including numeral keys, said numeral keys being connected to control step- 110 by-step movements of said carriage and also to control actions of said computing mechanism to accord with the numeral keys actuated, normally ineffective means actuatable from said carriage to control the action of 115 said computing mechanism, a series of locking elements connected to said numeral keys and coöoperating with one another to prevent the conjunctive action of two or more numeral keys, a universal member operable 120 by each and every one of said locking elements, shifting mechanism operated by said universal member to render said means 125

effective to control the action of said computing mechanism, and a locking element co-operating with said first-mentioned locking elements and connected to be actuated by 5 certain of said keys other than said numeral keys, so as to prevent the concomitant action of said numeral keys with certain others of said keys, said universal member having a cut-out portion enabling the free and independent movement of said last-mentioned locking element while it itself remains passive.

37. The combination with a traveling carriage, of a computing mechanism, a series 15 of keys including a set of numeral keys, said numeral keys being connected to control movements of said carriage and actions of said computing mechanism, the latter to accord with the numeral keys actuated, 20 locking elements connected to said numeral keys to prevent the concomitant actuation of more than one numeral key, normally ineffective means for controlling the action of said computing mechanism from said carriage, shifting mechanism operated by said locking elements for rendering said means effective, a locking element operated by certain of said keys other than said numeral keys to coöperate with said other locking 25 elements to interfere with the action of said numeral keys, said last-mentioned locking element moving free and clear of said shifting mechanism so as to enable a locking action independent of a controlling action of 30 said computing mechanism on the part of said carriage, and means coöperating with said locking elements for preventing a subsequent movement of any of said keys until the computing action started in said computing mechanism by a numeral key has 35 been completed.

38. The combination with a computing mechanism, of a series of numeral keys for controlling the action of said computing 45 mechanism, individual connections from said numeral keys to said computing mechanism, and means connected to said connections for blocking the computation-initiating movement of said connections subsequent to the 50 return of the active key until a computing action previously initiated thereby has been completed.

39. The combination with a computing mechanism, of a series of numeral keys, individual connections from said numeral keys to said computing mechanism to enable the initiation of computations of said computing mechanism by said numeral keys, a member universal to all of said connections and 55 actuatable thereby at a computation-initiating movement thereof, and means for preventing the movement of said universal member in a computation-initiating direction after a key which has initiated a computation has re-

turned, until such computation has been 65 completed.

40. The combination with a series of keys including numeral keys and other keys, of a computing mechanism, individual connections from said numeral keys to said computing mechanism to enable the control of computations of said computing mechanism by said numeral keys, locking means controlled from said computing mechanism for preventing a computation-initiating movement of any of said connections subsequent to a prior initiating movement of one of said connections until the computation initiated has been completed, and connections from said locking means to said keys other than said numeral keys for preventing the actuation of any of said other keys until the said initiated computation has been completed.

41. The combination with a computing 85 mechanism, of a set of keys including numeral keys and other keys, of individual connections between said numeral keys and said computing mechanism enabling the control by said numeral keys of computations in said computing mechanism, each of said connections having a locking element, said locking elements coöperating with one another to prevent conjunctive operation of two or more numeral keys, 90 a locking element actuated by the keys other than said numeral keys and coöperating with said other locking elements to prevent conjunctive actuations of said numeral keys and said other keys, and locking means actuated by said computing mechanism and coöperating with all of said locking elements to prevent actuation of any of said numeral keys and any of said other keys until an initiated 95 computation has been completed.

42. The combination with a traveling carriage, of tabulating mechanism for controlling movements of said carriage, computing mechanism, a series of numeral keys for controlling the action of said computing mechanism to accord with the numeral keys struck, and locking means controlled from said computing mechanism for preventing the actuation of said tabulating mechanism subsequent to the return of a numeral key 100 after having initiated a computation while the initiated computation is still extant.

43. The combination with a computing head, of a master wheel, said master wheel and said computing head having a relative 110 step-by-step denominational movement, a computing mechanism for running up numbers in said computing head through the intermediary of said master wheel, numeral keys for actuating said computing mechanism and controlling said step-by-step movements, and locking means controlled from said computing mechanism for preventing 115 120 125

said key-controlled step-by-step movements between said master wheel and said computing head subsequent to the return movement of a numeral key after initiating a computing action while the initiated computation is still extant.

44. The combination with a computing head comprising a series of computing wheels, of a master wheel coöperating with 10 said computing wheels individually to run up numbers, said computing head and said master wheel having a relative step-by-step denominational movement, computing mechanism for actuating said master wheel, numeral keys for controlling an initiating computing action of said computing mechanism, means actuatable by said numeral keys for initiating a relative movement between said computing head and said master wheel 20 in the same period that a computation is initiated by said numeral keys in said computing mechanism, and locking means for preventing a certain relative movement between said computing head and said master wheel 25 other than that determined by the striking of a numeral key in initiating a computation while the initiated computation is still extant.

45. The combination with a computing mechanism, of an escapement wheel for said computing mechanism, said escapement wheel having two movements, a major and a minor, for each computing action, and a pair of dogs coöperating with said escapement wheel to initiate the major movement of said escapement wheel first and the minor movement of said escapement wheel second in each computation.

46. The combination with registering mechanism, of a carriage traveling to determine denominational selections of said registering mechanism, computing mechanism for determining the computations run up in said registering mechanism, key mechanism solely for the purpose of effecting traveling movements of said carriage, and locking mechanism for said key mechanism controlled from said computing mechanism and maintained in action during a running 50 of said computing mechanism.

47. The combination with registering mechanism, of actuating mechanism for said registering mechanism, a carriage traveling to determine a relative traveling movement 55 between said registering mechanism and said actuating mechanism, tabulating mechanism for controlling major movements of said carriage, computing mechanism for determining the computation run into said registering mechanism by said actuating mechanism, and locking mechanism for preventing actuations of said tabulating mechanism and thus relative movements between said actuating mechanism and said register-

ing mechanism through said carriage traveling due to said tabulating mechanism while said actuating mechanism is running up numbers in said registering mechanism.

48. The combination with registering mechanism, of actuating mechanism for said registering mechanism, a carriage traveling to determine a relative traveling movement between said registering mechanism and said actuating mechanism, tabulating mechanism for controlling major movements of 75 said carriage, computing mechanism for determining the computation run into said registering mechanism by said actuating mechanism, locking mechanism for preventing actuations of said tabulating mechanism and thus relative movements between 80 said actuating mechanism and said registering mechanism through said carriage traveling due to said tabulating mechanism, while said actuating mechanism is running up 85 numbers in said registering mechanism, and releasing means for silencing said locking means, said releasing means being actuated by said computing mechanism at the termination of a computing action thereby. 90

49. The combination with registering mechanism, of actuating mechanism for said registering mechanism, a carriage traveling to effect relative movements between said registering mechanism and said actuating 95 mechanism, a spacing key for controlling movements of said carriage, computing mechanism for determining the computation run into said registering mechanism by said actuating mechanism, and locking 100 means for preventing an actuation of said spacing key, said locking means being maintained in action while said computing mechanism is in action and being controlled from said computing mechanism. 105

50. The combination with a computing mechanism, of a traveling carriage, numeral keys and others connected on the return movement thereof to permit a movement of said carriage, said numeral keys initiating 110 a computing operation by said computing mechanism, connections to said carriage for enabling a starting of a computing action initiated by a numeral key at such movement of said carriage, and a lock for preventing, after the return of a numeral key initiating a computing computation the subsequent actuation of said other keys while the computing action initiated is under way.

51. The combination with a computing 120 mechanism, of a carriage traveling to effect denominational selections for said computing mechanism, numeral keys and other controlling traveling movements of said carriage, said numeral keys initiating a computing operation by said computing mechanism, an escapement mechanism controlled 125 by said numeral keys so as to permit a

- traveling movement of said carriage on the return of an actuated numeral key, connections enabling said escapement mechanism to control the action of said computing mechanism after a numeral key has returned to permit said escapement mechanism to enable a movement of said carriage, and a lock dominated by said connections for preventing an action of said other keys.
- 10 52. The combination with computing mechanism, of a traveling carriage, keys controlling traveling movements of said carriage, some of said keys being numeral keys, computing mechanism controlled by 15 said numeral keys, connections enabling said carriage to control the action of said computing mechanism, and connection enabling said computing mechanism to control the

actions of said keys and thus the action of said carriage.

53. The combination with a computing mechanism, of a series of numeral keys for controlling the action of said computing mechanism, said numeral keys being free to return to their normal position after starting a computing action, even before the computing action is finished, and locking means for preventing the subsequent actuation of any numeral key during the remaining period of an active computation after the 30 return to normal position of the numeral key starting the computing action.
